UNITED STATES PATENT OFFICE.

EUGENE HIGGINS, OF JACKSON, MICHIGAN, ASSIGNOR TO JACKSON MACHINE TOOL CO., OF JACKSON, MICHIGAN.

DIE-SINKING MACHINE.

1,310,656.

Specification of Letters Patent. Patented July 22, 1919.

Application filed August 19, 1918. Serial No. 250,429.

To all whom it may concern:

Be it known that I, EUGENE HIGGINS, a citizen of the United States, residing at Jackson, county of Jackson, State of Michigan, have invented certain new and useful Improvements in Die-Sinking Machines, of which the following is a specification.

This invention relates to improvements in die sinking machines.

10 The main objects of this invention are:

First, to provide an improved die sinking machine of large capacity.

Second, to provide an improved die sinking machine which is capable of performing various kinds of work.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing, forming a part of this specification, in which:

Figure I is a front perspective of a structure embodying the features of my invention.

30 Fig. II is a plan view.

Fig. III is a plan of the base.

Fig. IV is an enlarged detail section through the head on a line corresponding to line 4—4 of Figs. I, II, V and VI, parts 35 being shown in full lines for convenience in illustration.

Fig. V is a detail vertical section through the head on a line corresponding to line 5—5 of Figs. VI and XI, parts being shown 40 in full lines.

Fig. VI is a detail horizontal section through the head on a line corresponding to line 6—6 of Figs. IV, V and IX.

Fig. VII is a detail section on a line 45 corresponding to line 7—7 of Fig. VI, showing details of the locking features for the milling spindle and cutter driving gears.

Fig. VIII is an enlarged detail perspective of the gear locking means shown in 50 Fig. VII.

Fig. IX is a horizontal section on a line corresponding to line 9—9 of Fig. X, showing details of the cutter driving means.

Fig. X is a detail vertical section on a line 55 corresponding to line 10—10 of Fig. V,

showing details of the cutter and its driving means.

Fig. XI is a detail section of the parts shown in Fig. X in another position and illustrating the operation thereof. 60

In the drawing similar reference characters refer to similar parts throughout the several views, and the sectional views are taken looking in the direction of the little arrows at the ends of the section lines. 65

Referring to the drawing, the base 1 is preferably provided with three feet, 2, 2' and 3, shown by dotted lines in Fig. III, arranged in a triangular relation so as to provide a three point support for the machine, facilitating its setting and providing rigidity. When installing the machine these feet only rest upon the foundation and the machine is leveled by shimming under, these feet solidly supporting it. The column 4 is provided with a suitable way 5 for the head 6. The table 7 of the bed is carried by the cross rail 8 slidably mounted on the way 9, the table being adjustably mounted on the cross rail and the cross rail 80 adjustably mounted on the base, both being provided with hand and power feed means, not shown, so that a die block bolted to the table may be brought under any of the tools carried by the head. 10 represents the feed 85 screw for the head and 11 the vertical drive or power shaft. The driving connections for the screw and shaft are not illustrated as they form no part of this invention.

The head is provided with a main or large 90

milling cutter spindle 12, an auxiliary or small milling spindle 13 and a cutter operating carriage 14, see Fig. V, the cutter illustrated being of the type designated by the trade as a "cherry" tool or "cherrying" 95

cutter. The spindle 12 is provided with a journal 12' at its lower end, a bearing 12" being provided therefor. The spindle 12 is also provided with a double thrust ball bearing 100

adjustably supported so that a limited vertical adjustment of the spindle is provided to secure its rigidity. This thrust bearing is best shown in Figs. IV and V and comprises an internally threaded box 15 mounted within the head by the screws 16. 105

The bearing sleeve 17 carries the race members 18, while the spindle carries the intermediate thrust ring member 19. Adjusting rings 20 are threaded into the box 15 which has openings 21 therein alined with open- 110

ings 22 in the walls of the head adapted to receive a rod or tool to engage in the holes 23 for adjusting the rings. Set screws 24 are provided for locking the rings in their 5 adjusted positions. The upper end of the spindle is supported by a bearing, designated generally by the numeral 25. The spindles are driven from the drive shaft 11 which has a driving gear 27 spindle thereto. 10 The jack shaft 28 is mounted parallel with the spindle 12 and is connected to shaft 11 by the gear 27 on drive shaft 11 and gear 29 on the stub shaft 30 and gear 31 on shaft 28,—see Fig. IV. The gear 31 is keyed 15 to the shaft 28. The spindle driving gear 32 is rotatably mounted upon the driven shaft 28 and meshes with gear 33 on the spindle. A clutch member 34 is splined to the jack shaft to coact with a clutch member 20 on the gear 32 thereby providing a disengageable driving connection for the main spindle.

The auxiliary spindle 13 is provided with oppositely disposed conical bearings 35 and 25 36 at its lower end and a cylindrical bearing 37 at its upper end, see Fig. V.

An adjusting ring 38 is provided for the lower bearings. This form of bearing is well adapted to receive both radial and end 30 loads to which the spindle is subjected in use. The bearings 35 and 36 are carried in a sleeve 39 vertically adjustable within the head. The vertical adjustments of this sleeve are effected by the hand wheel 40. 35 The connection for the hand wheel spindle to the sleeve are not illustrated.

The spindle bracket 41 carrying the sleeve 39 is preferably detachably secured to the head 6 by the bolts 42 so that the second 40 spindle can be supplied, if desired, as an attachment.

The spindle 13 is provided with a gear 43 at its upper end connected by the gears 44 and 45, shown conventionally in Fig. II, to 45 the gear 46 on the jack shaft 28. The gear 43 is splined to the spindle 13. The gear 46 is rotatably mounted on the shaft 28 and provided with an annular clutch flange 47 having the expanding clutch member 48 50 therein, the clutch member 48 being secured to the shaft. A lever 49 is pivoted on the head at 50 to actuate the clutch member 51,—see Fig. IV.

When it is desired to drive the auxiliary 55 spindle the lever 49 is manipulated to engage the clutch for the gear 46.

The circular cutter 52 has cutting teeth on its periphery and sides and is supported for vertical and oscillating movement. The 60 cutter 52 is provided with a shank 53 engaged in the socket or chuck 54 of the holder 55 which is mounted in the reciprocating carriage 14. This carriage 14 has curved or segment-like ways 56 for the segment-like 65 guides 57 projecting oppositely from the

sides of the holder. The carriage reciprocates in V-shaped ways 58 and 59, the way 59 being adjustably supported by means of the adjusting and set screws 60 and 61,—see Fig. V. Screws 62 and 63 hold the ways in the 70 head laterally, the way 59 having enlarged holes to receive the screws permitting the lateral movement of the way so that a very close sliding fit for the carriage in its way is provided. For convenience in assembling 75 the carriage is formed in two parts 64 and 65 divided along vertical lines and secured together by screws 66. Shims 67 may be arranged between the carriage members to accommodate for wear or secure a nice fit. 80 The carriage is actuated in one direction by the cam 68 on shaft 69 having worm gear 70 thereon meshing with gear 71 on the jack shaft 28. This gear 71 is rotatably mounted on the shaft to be connected thereto by the 85 clutch 34. The carriage 64 is connected to a crank 72 by a pitman or connecting rod 73. On the crank 72 is an arm 74 connected by the link 75 to the arm 76 on the rock shaft 77. The rock shaft arm 76' is connected to 90 the spring 78 which actuates the carriage on its work stroke. The cam 68 acts upon the roller 79 on the arm 80 of the rock shaft 77. The arm 74 is connected to the crank 72 by the clutch 81 adjusted by means of the hand 95 wheel 82 threaded upon the end of the shaft and held in its adjusted positions by the spring pin or detent 83. This provides for the disengaging or throw out of the cutter and for the adjustment of its feed to the 100 work. To simultaneously oscillate the cutter its arm 84 is connected by the link 85 to the swinging arm 86 having a longitudinal groove engaging the roller 87 on the cam 68,—see Fig. IX.

The hand feed for the head is shown in 105 Fig. VI in which the shaft 88 is provided with the hand wheel 89 and with the pinion 90 meshing with the pinion 91 on the feed screw.

With this arrangement of parts, when the cutter starts on its forward or cutting stroke it at the same time lowers to the work. At the end of its cutting stroke it is raised from the work. The cutter is lifted from its work by the cam and the spring forces the cutter to its work. However, the strength of the spring is such that it cannot be overloaded by taking too heavy a cut for the parts so that before any damage is done to 110 the parts the spring will yield and a shallower cut be taken when the operator will observe that the depth of cut is too great and it can be regulated accordingly.

To relieve shock, as the cutter is brought 115 to its work I provide buffer springs 92 seated in bores 93 of the carriage and supported by brackets 95,—see Fig. V.

The clutch member 34 for the gears 32 and 71 is shifted from the lever 96 mounted 130

on the rock shaft 97 having an arm 98 engaging the clutch, as best shown in Figs. I, VII, and VIII. To alternately lock the gears 32 and 71 as the clutch is shifted from one to the other I provide locking pins 99 and 100, respectively, supported in the holders 101 to be projected by the springs 102. These pins are retracted by the cam rod 103 adapted to engage the projecting pins 104 as the cam rod is reciprocated by the arm 98 which has a pin 105 engaging the cam rod as shown in Figs. VII and VIII. In Fig. VII the pin 100 is shown engaged with the gear 71, the other pin being retracted so as to permit the driving of the main spindle.

The main spindle is provided with a chuck 106 having a tapered shank to fit the tapered socket 107 in the spindle. A rod 108 disposed longitudinally through the spindle and provided with a head 109 is threaded into the inner end of the chuck shank,—see Fig. IV.

With this arrangement of parts I provide a structure which is adapted for very heavy die cutting work and is of large capacity and convenient in operation.

I have illustrated and described my improvements in the form in which I have embodied them for the market. I have not attempted to illustrate certain modifications and adaptations which I contemplate as I believe the disclosure made will enable those skilled in the art to which my invention relates to embody or adapt the same as may be desired.

Having thus described my invention, what I claim as new and desire to secure by Letters Patent, is:

1. The combination of a reciprocating tool holder carriage, a cutter, a holder for said cutter having segmental slides and an arm projecting upwardly above said slides, said carriage having segmental ways for said slides, a crank mounted above said carriage, a pitman connecting said crank to said carriage, an arm on said crank adjustably and releasably secured thereto, a rock shaft having arms thereon, a link connecting an arm on said rock shaft to said arm on said crank, an actuating spring connected to an arm on said rock shaft, a cam, an arm on said rock shaft provided with a roller traveling on said cam whereby the carriage is retracted, a pivoted arm provided with a longitudinal groove disposed at the side of said cam, a roller on said cam coacting with said groove whereby the arm is oscillated as the cam is rotated, and a link connecting said arm on said tool holder to said pivoted arm.

2. The combination of a reciprocating tool holder carriage, a cutter, a holder for said cutter having segmental slides and an arm projecting upwardly above said slides, said carriage having segmental ways for said slides, a crank mounted above said carriage,

a pitman connecting said crank to said carriage, an arm on said crank, a rock shaft having arms thereon, a link connecting an arm on said rock shaft to said arm on said crank, an actuating spring connected to an arm on said rock shaft, a cam, an arm on said rock shaft provided with a roller traveling on said cam whereby the carriage is retracted, a pivoted arm provided with a longitudinal groove disposed at the side of said cam, a roller on said cam coacting with said groove whereby the arm is oscillated as the cam is rotated, and a link connecting said arm on said tool holder to said pivoted arm.

3. The combination of a reciprocating tool holder carriage, a cutter, a holder for said cutter having segmental slides, said carriage having segmental ways for said slides, a crank mounted above said carriage, a pitman connecting said crank to said carriage, an arm on said crank adjustably and releasably secured thereto, a rock shaft having arms thereon, a link connecting an arm on said rock shaft to said arm on said crank, an actuating spring connected to an arm on said rock shaft, a cam, an arm on said rock shaft provided with a roller traveling on said cam whereby the carriage is retracted, and operating means for said holder comprising said cam.

4. The combination of a reciprocating tool holder carriage, a cutter, a holder for said cutter having segmental slides, said carriage having segmental ways for said slides, a crank mounted above said carriage, a pitman connecting said crank to said carriage, an arm on said crank, a rock shaft having arms thereon, a link connecting an arm on said rock shaft to said arm on said crank, an actuating spring connected to an arm on said rock shaft, a cam, an arm on said rock shaft provided with a roller traveling on said cam whereby the carriage is retracted, and operating means for said holder comprising said cam.

5. The combination of a reciprocating tool holder carriage, vertically disposed opposed V-shaped ways therefor, one of said ways being laterally adjustable, a circular cutter having peripheral and side teeth, a holder for said cutter having segmental slides on its sides, said carriage having opposed segmental ways for said slides, a crank, a pitman connecting said crank to said carriage, an arm on said crank provided with a clutch member, a coacting clutch member splined to said crank, a clamping nut for said clutch whereby said arm may be adjustably secured to the crank, an actuating means for said carriage connected to said arm on said crank, and an actuating means for said tool holder.

6. The combination of a reciprocating tool holder carriage, vertically disposed ways therefor, a circular cutter having peripheral and side teeth, a holder for said cutter hav-

ing segmental slides on its sides, said carriage having opposed segmental ways for said slides, a crank, a pitman connecting said crank to said carriage, an arm on said crank 5 provided with a clutch member, a coacting clutch member splined to said crank, a clamping nut for said clutch whereby said arm may be adjustably secured to said crank, an actuating means for said carriage connected to said arm on said crank, and an actuating means for said tool holder.

7. The combination of a reciprocating tool holder carriage, a circular cutter having peripheral and side teeth, a holder for said cutter having segmental slides mounted in said carriage, a crank mounted on said head above said carriage, a pitman connecting said crank to said carriage, an arm on said crank, a rock shaft having arms thereon, a link connecting said rock shaft to said arm on said crank, an actuating spring connected to said rock shaft, means for actuating said rock shaft to return the carriage, and means for actuating said cutter holder operatively connected to said carriage actuating means, for the purpose specified.

8. The combination of a reciprocating tool holder carriage, a cutter, a holder for said cutter mounted for oscillating movement on said carriage, a crank, a pitman connecting said crank to said carriage, an arm on said crank adjustably and releasably secured thereto, means for actuating said crank connected to said arm thereof comprising a spring for advancing said carriage and a cam for retracting said carriage, a pivoted arm actuated by said cam, and a link connecting said tool holder to said pivoted arm.

40 9. The combination of a reciprocating tool holder carriage, a cutter, a holder for said cutter mounted for oscillating movement on said carriage, a crank, a pitman connecting said crank to said carriage, 45 means for actuating said crank connected to said arm thereof comprising a spring for advancing said carriage and a cam for retracting said carriage, a pivoted arm actuated by said cam, and a link connecting said 50 tool holder to said pivoted arm.

10. The combination of a reciprocating tool holder carriage, a cutter, a holder for said cutter mounted for oscillating movement on said carriage, a crank, a pitman connecting said crank to said carriage, an arm on said crank adjustably and releasably secured thereto, means for actuating said crank connected to said arm thereof comprising a spring for advancing said carriage 55 and a cam for retracting said carriage, and means for actuating said holder comprising said cam.

60 11. The combination of a reciprocating tool holder carriage, a cutter, a holder for said cutter mounted for oscillating move-

ment on said carriage, a crank, a pitman connecting said crank to said carriage, means for actuating said crank connected to said arm thereof comprising a spring for advancing said carriage and a cam for retracting said carriage, and means for actuating said holder comprising said cam. 70

12. The combination of a reciprocating tool holder carriage, a cutter, a holder for said cutter mounted for oscillating movement on said carriage, means for actuating said carriage comprising a spring for advancing said carriage and a cam for retracting said carriage, and means for actuating said tool holder comprising said cam. 75

13. The combination of a reciprocating tool holder carriage, a cutter, a holder for said cutter mounted for oscillating movement on said carriage, means for actuating said carriage comprising a spring for advancing said carriage, and positive means for retracting said carriage, and means for actuating said tool holder comprising said cam. 80

14. The combination with a horizontally adjustable table and an overhanging head, of a reciprocating tool holder carriage on said head, a circular cutter having peripheral and side teeth, a holder for said cutter mounted to oscillate on said carriage about 85 the axis of the cutter, and means for reciprocating said carriage and oscillating said tool holder in synchronism comprising a carriage actuating spring. 90

15. The combination with a horizontally adjustable table and an overhanging movable head, of a spindle carried thereby, driving means for said spindle comprising a jack shaft, a spindle driving gear on said jack shaft, a coacting gear on said spindle, 105 a reciprocating tool holder carriage on said head, a cutter, a holder for said cutter mounted for oscillating movement about the axis of the cutter, means for reciprocating said carriage and oscillating said cutter 110 holder in synchronism, comprising a driving gear on said jack shaft, a clutch on said jack shaft disposed between said driving gears and adapted to secure either of said gears to said jack shaft, and a locking means 115 for said gears actuated by the shifting of said clutch. 120

16. The combination with a horizontally adjustable table and an overhanging movable head, of a spindle carried thereby, driving means for said spindle comprising a jack shaft, a spindle driving gear on said jack shaft, a coacting gear on said spindle, a reciprocating tool holder carriage on said head, a cutter, a holder for said cutter mounted for oscillating movement about the axis of the cutter, means for reciprocating said carriage and oscillating said cutter 125 holder in synchronism, comprising a driving gear on said jack shaft, and a clutch on said 130.

jack shaft disposed between said driving gears and adapted to secure either of said gears to said jack shaft.

17. In a structure of the class described, 5 the combination with a head, of a feed means therefor, a main spindle, an auxiliary spindle, a supporting bracket therefor detachably mounted on said head, a manually operated means for feeding said auxiliary 10 spindle independent of said head, a jack shaft having driving connections to said main spindle, and driving connections from said jack shaft to said auxiliary spindle including a clutch.

15 18. In a structure of the class described, the combination with a head, of a feed means therefor, a main spindle, an auxiliary spindle, a supporting bracket therefor detachably mounted on said head, a manually 20 operated means for feeding said auxiliary spindle independent of said head, and means on said head for driving said spindle.

25 19. In a structure of the class described, the combination of a main spindle, an auxiliary spindle, a jack shaft having driving 30 connections with said main spindle comprising a clutch, a train of driving gears for said auxiliary spindle comprising a gear on said jack shaft, and a clutch for connecting said gear to said jack shaft, and manually 35 operated means for feeding said auxiliary spindle.

40 20. In a structure of the class described, the combination of a main spindle, an auxiliary spindle, a jack shaft having driving 35 connections with said main spindle comprising a clutch, a train of driving gears for said auxiliary spindle comprising a gear on said jack shaft, and a clutch for connecting 45 said gear to said jack shaft.

21. The combination with a spindle, of a 45 tapered journal and bearing therefor at the lower end of said spindle, a thrust bearing comprising a thrust ring on said spindle, a 50 pair of coacting race members at each side thereof and bearing balls interposed between

said thrust ring and race members, an adjustable sleeve in which said race members are mounted, a pair of threaded adjusting rings at the ends of said sleeve, a bearing 50 for the upper end of said spindle, and driving means for said spindle comprising a gear disposed between the upper end and said thrust bearing.

22. The combination with a spindle, of a 55 tapered journal and bearing therefor at the lower end of said spindle, a thrust bearing comprising a thrust ring on said spindle, a pair of coacting race members at each side thereof and bearing balls interposed between 60 said thrust ring and race members, an adjustable sleeve in which said race members are mounted, and a pair of threaded adjusting rings at the ends of said sleeve.

23. The combination with a spindle, of a 65 tapered journal and bearing therefor at the lower end of said spindle, a thrust bearing comprising a thrust member on said spindle, coacting bearing members, an adjustable 70 sleeve in which said coacting members are mounted, a pair of threaded adjusting rings at the ends of said sleeve, a bearing for the upper end of said spindle, and driving means for said spindle comprising a gear disposed between the upper end and said thrust 75 bearing.

24. The combination with a spindle, of a tapered journal and bearing therefor at the lower end of said spindle, a thrust bearing 80 comprising a thrust member on said spindle, coacting bearing members, an adjustable sleeve in which said coacting members are mounted, and a pair of adjusting rings at the ends of said sleeve.

In witness whereof, I have hereunto set 85 my hand and seal in the presence of two witnesses.

EUGENE HIGGINS. [L. s.]
